W. E. GARDNER

KNOCKDOWN BOX OR CRATE

Filed June 10, 1924

UNITED STATES PATENT OFFICE.

WILLIAM E. GARDNER, OF GREENCASTLE, PENNSYLVANIA.

KNOCKDOWN BOX OR CRATE.

Application filed June 10, 1924. Serial No. 719,079.

The object of my invention is to avoid the great money loss which occurs from the use of the ordinary shipping boxes or crates which are of such construction that re-use for shipping purposes is not economically possible, and to that end my invention consists in a shipping box or crate so constructed that it may be returned to the shipper in a flat or knock down condition so that the freight or shipping cost will be so low as to make repeated use of the same box or crate desirable or advantageous. In making my invention I have had in view the utilization of standard or stock materials which means a great reduction in cost compared with the use of parts that require specially to be made, and while I have had in view the easy and rapid assemblage of the parts for serving as a goods container and the easy and quick dismantling thereof I have also had in view a construction which will make the box or crate when in its goods-containing form of all required rigidity and strength to withstand the rough usage of freight handling. I have also had in view a construction which will lend itself readily to the use of a seal.

My invention consists in whatever is described by or is included within the terms or scope of the appended claims.

In the accompanying drawings:

Fig. 1 is a perspective view of a shipping box embodying my invention in its goods-containing form;

Fig. 2 is a similar view showing portions of the box separated;

Fig. 3 is a detail view in section at one of the corners of the box.

The top, bottom, side and end walls of the box may be of wood, sheet metal or other material and if wood each wall may be formed of several strips or pieces joined together permanently or several pieces that have no connection with one another, but which are held in proper position when the box is made up or assembled. In the drawings said walls, 10, are shown as made of strips or pieces of wood joined together in a square or rectangular form.

The several walls are held in an assembled relation to form a cubical box by a metal frame-work which consists of iron or steel angles, 11, one for each of the corners of the box so that there are twelve such angles all being of like length and other dimensions

and each angle near each end having in each flange a hole, 12, so that when the angles are assembled with the adjacent ends of three overlapping the holes, 12, of the contiguous flanges will register or align with one another and with the corresponding ones at the opposite corner on the same side of the box so that through the alining or registering holes a rod or bar, 13, may be passed from side to side of the box, the rod or bar being sufficiently long so that its ends protrude on the outside of the angles, and such ends being threaded they will receive the clamping nut, 14. If desirable the rods, 13, at one end may have a head so that a nut will only be required at one end of each rod. The rods are sufficiently spaced from the inner surfaces of the angles to allow the placing of the box walls, 10, between the rods and the adjacent flanges and thus the walls, 10, will be confined in place. It will be understood that the angles and walls are assembled in such order that the building up of the box proceeds progressively.

As shown in Fig. 1 the seal wire, 15, may be threaded through the holes of the overlapping angles and it may be passed through a hole in a rod, 13, which will be above the nut when the latter is screwed tight so that it will serve as a nut lock, but if desired the seal wire may be passed around the rod between the nut and the angle flange.

It will be understood that when the box is in a knock-down condition the walls, 10, may be placed one upon another and the angles nested together and the rods laid parallel with one another and with the angles, the angles and rods being held together in a compact arrangement by wires and they and the walls being suitably secured together so that during reshipment they will not become separated.

When the size of the box or crate requires it, rods or bars similar to those at the corners may be employed at intermediate points, the angle flanges being provided with holes for their passage therethrough.

Since the rods pass one another the holes in the angle flanges must be arranged to permit this. To enable this to be done without requiring the displacement of the holes themselves, they may be sufficiently larger than the diameter of the rods to allow the necessary side displacement of the rods, and the nuts, of course, will be sufficiently large

to overlap the flanges at the sides of the holes.

What I claim is:

1. A shipping box or crate of cubical form comprising walls and a supporting frame, walls and frame being readily separable from one another, and walls and frame-members adapted to be put together in a knock down condition, said frame being composed of a plurality of similar angles having perforations near each end through both flanges of the angles and bars having portions to pass through alining perforations and means to hold the angles and bars in assembled wall supporting position there being an angle at each corner of the crate.
2. A shipping box or crate of cubical form comprising walls and a supporting frame, walls and frame being readily separable from one another, and walls and frame-members adapted to be put together in a knock down condition, said frame being composed of a plurality of similar angles having perforations, near each end through both flanges of the angles and bars having portions to pass through alining perforations and means to hold the angles and bars in

assembled wall supporting position there being an angle at each corner of the crate, said bars being spaced from the inner sides 20 of the angles and the walls entering the spaces between the bars and the angle flanges.

3. A shipping box or crate comprising four side walls and top and bottom walls 25 of substantially the same dimensions and a supporting frame composed of a plurality of similar angles of substantially the same length and corresponding in number with all the corners of the box and reaching from top to bottom and from side to side of the box and within the flanges of which angles all said walls are placed and said walls and angles being readily separable and said angles having near each end perforations 40 through both flanges of the angles and bars having portions that pass through alining angle perforations to the exterior of the angles and threaded on their projecting portions and removable nuts on the threaded 45 portions outside the angles.

In testimony whereof I hereunto affix my signature.

WILLIAM E. GARDNER.
